UNITED STATES PATENT OFFICE

DELOS SEWELL, OF BUFFALO, NEW YORK, ASSIGNOR TO THE GRAND RAPIDS SCALPER, GRADER, AND PURIFIER COMPANY, OF GRAND RAPIDS, MICHIGAN.

SEPARATOR.

SPECIFICATION forming part of Letters Patent No. 546,252, dated September 10, 1895.

Application filed February 16, 1891. Serial No. 381,719. (No model.)

To all whom it may concern:

Be it known that I, DELOS SEWELL, a citizen of the United States, residing at Buffalo, in the county of Erie and State of New York, 5 have invented a new and useful Improvement in Separators, of which the following is a specification.

This invention pertains to mills, and has for its object a scalper and chop-grader in which the separation between the various qualities of material is effected by a continuously-moving current of air in combination with a vibrating sieve. The force and direction of the air is regulated by means of the mechanism described, and which operates across and obliquely upward against the falling particles of the "break or chop" scattered into it by means of the said scalper-sieve placed at the upper part and within the casing of the separator. My separator is especially designed to be used in grading the material coming from the rolls of roller-mills, after having been subjected to the process of partial crushing and partial grinding employed in roller-mills. 15 This material in this condition is sometimes known as "break," and is called "first break" and "second break," in accordance with the number of times it has passed through the rolls, and after each break it is passed through the separator and divided into parts of various degrees of fineness or lightness, and those parts which have not been sufficiently broken up are returned to the rolls for the succeeding breaking process and the bran and other material from which all of the flour particles 20 have been removed is separated out and laid aside. In my separator I employ what may be termed a "rotary air-current"—that is, the machine is so constituted that a rotating fan sets in motion the air which is contained within the casing of the machine, and it is not intended to draw into the casing any air from the outside or to force out any of the contained air, but is designed to produce currents within the casing itself and to regulate those currents, so that they will be concentrated and active in some parts of the interior of the casing, while the air will be dispersed and comparatively quiet on other parts of the 25 interior. At the same time the actively-moving currents of air are to be so regulated as

to take up and carry into the settling-chamber only the very lightest or dust particles, permitting the heavier parts to drop through the current of air and out of the casing at the 55 proper delivery-openings. I accomplish these results by the hereinafter-described mechanism arranged and shown in the drawings, and as described in the specification.

Figure 1 is a vertical section of the casing 60 and its included parts. Fig. 2 represents a section taken horizontally at X X of Fig. 1. Fig. 3 is an elevation of the machine, showing the various outlets and conveyers and also the means for driving the same. Fig. 4 is a 65 partial plan view of the grading-sieve, showing the sections of different degrees of fineness.

The casing A has an inlet-opening a and outlet-openings 1 2 3 4 5, the outlet-openings 70 4 5 having conveyers in them. At about the middle portion of the casing A is a fan B, of which the shaft b extends out through the side of the casing to receive its support and to receive the driving-wheel by means of which 75 the fan is rotated. At either end of the fan, leading into the eye of the fan, is a flue C c, extending downward along the side of the casing to near the bottom, then turning with the outline of the casing. Each flue extends upward to the top of the casing, where the two communicate with a central flue D, that leads down between the two side flues C c and opens at d into the main chamber of the 80 separator. Around the fan B are diaphragms 85 F H and adjustable valves E G, which form the walls of an interior chamber within which the fan rotates, and of which the valvular portion of the wall can be adjusted to permit the passage of a large or small amount of air 90 from the fan outward. The walls of the interior chamber are represented by E F G H, of which the part F is without opening except a small opening closed by the drop-valve f at the junction of F and the casing A. The 95 part H above the fan may be made without openings or with openings, preferably with one or two small openings. The parts E G are composed of slat-valves arranged to be operated like the slats of a window-blind, so 100 as to permit the passage between them of an amount of air proper for the work to be done,

depending upon the coarseness of break. In front of the slat-valves E are one or more lines of cant-boards I lying across the space below the scalper-sieve J, and in front of the valve E similar cant-boards K are located across the space in front of G and below the portion of the sieve J which lies beyond the valve G. The cant-boards i K receive the falling meal upon their upper surface and scatter it into the current of air passing between them, retarding the descent of the meal or break, and causing the air to act more efficiently in separating and grading it.

In front of the cant-boards I is a diaphragm L, compelling the air to dip beneath it in its passage from the fan around the walls of the separator until it enters the upflue B' on its way to the eye of the fan. The air passing up between the cant-boards I i and dipping downward around L forms an eddy, which acts in a very efficient manner to take up and carry along with it the smaller portions or dust of the meal. At the upper end of the diaphragm L is a bumper M, against which the end of the scalper-sieve J strikes as it is moved up and down by means of the cam O. A second bumper m is located near the upper end of the scalper-sieve and beneath it, and is struck by the sieve J with the down stroke of the sieve at the same time that the bumper M receives the end stroke. The sieve J is suspended from springs SS, which are attached to the sides of the casing A or to the bar T, made firm to the casing. This sieve is divided into sections of different degrees of fineness m^1 m^2 m^3 , as illustrated in Fig. 4, the finest being at the head of the machine.

Across the framework of the sieve is a bar or cross-piece p, on the under side of which are wedge-shaped pieces P, and held in position by means of a bolt and setting-nut. Underneath each wedge is a cam O on a shaft that extends to the outside of the casing. The rotation of the shaft, carrying the cam with it, raises the sieve and moves it endwise, then lets it drop and strike against the bumpers M m, and the shaking motion is suddenly stopped. This acts to compel the lighter material to fall through the meshes of the sieve, especially irregular pieces that might otherwise hang to the wires of the sieve. The lightest material of all passes with the eddying current of air between the cant-boards I i, and is carried with the current of air around the walls of the case until it finally settles at 4 and is delivered through the conveyer at that point.

Fine middlings passing through the screen directly under the feed-spout, after having the finer material blown out from them by means of air coming through the valve G, settle at 5 and are conveyed away by the conveyer. Coarser middlings and coarser particles are delivered through the outlets, break chop at 6 and coarse middlings at 3, and bran is delivered at the outlet 1, so that a separator such as is shown in the drawings will grade the

break or chop into five different qualities of material. The effective action of the air-current is greatly increased by the eddies that are formed by the arrangement of the various cant-boards and tipping diaphragms, which are so arranged as to produce a number of eddies or minor circular currents that tend to keep the material in motion, and thus compel the separation of the various parts by the combined action of the air-currents and gravity, and evenness of the grading of the material is aided by the peculiar character of the valves E G, which allow the air to pass between the slats in a number of thin streams rather than in a single large stream. These thin streams uniting as they emerge from between the slats pass forward through the falling meal in an evenly-moving mass, in which the force is everywhere uniform, and the effective results are much better than where a smaller stream of air under greater tension is employed.

The housing of the fan—that is, the parts which surround the fan—should be far enough from the fan-blades to furnish chambers of considerable size, in which the air may equalize itself before passing through the valves. Drop valves f g are arranged to permit the escape of any dust that may get inside of the fan-housing or the flue leading to the eye of the fan. The valve f hangs perpendicular and is held in place by gravity until the weight of accumulated material opens it. The valve g is hung on the upper side and is closed against the opening before which it hangs by the pressure of the air under the operation of the fan until the weight of accumulated material opens it.

Having thus described my invention, what I claim as novel, and desire to have secured to me by Letters Patent, is—

1. In a separator, the combination of a casing having inlet and outlet openings, a fan revolving freely within said casing, a housing for said fan, having openings through the walls thereof and the described slat valves to regulate the flow of air through said openings from within outward, and an air flue, leading from without said housing into the eye of the fan, substantially as and for the purpose described.

2. In a separator, the combination of a casing having inlet and outlet openings, a fan revolving freely within said casing, a housing for said fan having openings through the walls thereof, and the described slatted valves to regulate the flow of air through said openings from within outward, an air flue leading from without said housing into the eye of the fan, and a scalper sieve located within said casing, adapted to be vibrated, substantially as and for the purpose described.

3. In a separator, the combination of an outer casing having a feed opening and outlet openings; a fan freely revolving within said casing, a system of diaphragms and slat

valves forming a housing around said fan; a scalper sieve arranged to receive material from the feed opening and distribute it across the interior of said casing into the moving bodies of air, a slat valve having numerous openings and arranged to direct the air from said fan upward toward the tail of said sieve and a dip-board L arranged at the tail of said sieve as described to produce an eddy in the air current, and more thoroughly aspirate the material passing over the tail of the sieve as described.

4. In a separator, the combination of a cas-

ing, a fan revolving therein, a housing for said fan composed of diaphragms and valve closed 15 openings as described; a flue leading from without said housing into the eye of said fan and valves arranged to permit the escape of dust improperly collecting within said housing, substantially as and for the purpose de- 20 scribed.

DELOS SEWELL.

In presence of—

CHARLES F. BURTON,
EFFIE I. CROFT.
